CLAIM

The ornamental design for a surface configuration of an instrument display panel for a vehicle, as shown and described.

DESCRIPTION

FIG. 1 is a front view of a first embodiment of a surface configuration of an instrument display panel for a vehicle according to our novel design; and, FIG. 2 is a front view of a second embodiment of the surface configuration of an instrument display panel for a vehicle according to our novel design. The broken lines are for illustrative purposes only and form no part of the claimed design.
